(57) **CLAIM**

The ornamental design for modular steps as shown and described.

DESCRIPTION

FIG. 1 is a perspective view of the modular steps, showing my new design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof;

FIG. 8 is a top perspective view of a top block of the modular steps thereof;

FIG. 9 is a side view of a top block of the modular steps thereof;

FIG. 10 is a top perspective view of a first middle block of the modular steps thereof;

FIG. 11 is a side view of a first middle block of the modular steps thereof;

FIG. 12 is a top perspective view of a second middle block of the modular steps thereof;

FIG. 13 is a side view of a second middle block of the modular steps thereof;

FIG. 14 is a top perspective view of the bottom block of the modular steps thereof;

FIG. 15 is a side view of the bottom block of the modular steps thereof;

FIG. 16 is a top perspective view of a first middle block of the modular steps with hollow center;

FIG. 17 is a side view of a first middle block of the modular steps with how center;

FIG. 18 is a perspective view of a second middle block of the modular steps with hollow center; and,

FIG. 19 is a side view of a second middle block of the modular steps with hollow center.

1 Claim, 11 Drawing Sheets
